UNITED STATES PATENT OFFICE.

DAVID G. WILLIAMS, OF PORT HURON, MICHIGAN, ASSIGNOR OF ONE-HALF
TO EDWARD PERCIVAL, OF SAME PLACE.

SPOON.

SPECIFICATION forming part of Letters Patent No. 280,985, dated July 10, 1883.

Application filed February 8, 1883. (No model.)

To all whom it may concern:

Be it known that I, DAVID G. WILLIAMS, of Port Huron, in the county of St. Clair and State of Michigan, have invented new and useful Improvements in Spoons; and I do hereby declare that the following is a full, clear, and exact description thereof, reference being had to the accompanying drawings, which form a part of this specification.

10 The nature of this invention relates to certain new and useful improvements in spoons, by means of which those who wear mustaches are enabled to eat soup and other liquid food without the disagreeable consequences usually attached to eating such food—viz., smearing their mustaches.

The invention consists in providing the spoon with a guard which will prevent the dipping therein of the ends of the mustache.

20 The guard is attached to one side of the bowl of the spoon, the opposite side being open to allow the proper dipping of the spoon in the soup or the like.

Figure 1 represents a mustache-spoon, and Fig. 2 a transverse section through the line *x* of Fig. 1.

In the accompanying drawings, which form a part of this specification, A represents a spoon of ordinary construction, provided with 30 the guard B, secured upon one side of the bowl of the spoon in such a manner as to allow the free discharge of the contents of the spoon without any of the disagreeable results which pertain to the use of the spoons of ordinary construction, as above noted.

In Fig. 1 it will be noticed that the guard B is secured by hinge *b* to the side of the spoon. This form of guard is designed especially for the use of those who wear their

beard upon their upper lips, and enables 40 them to eat soup without dipping the hair into it.

It will be observed that the space between the guard and the edge of the bowl upon one side is sufficient to allow the soup, or the like, to be dipped up in the bowl, but that when placed to the mouth the mustache will be kept from contact with the contents of the bowl by the guard. The hinge *b* is so formed that the guard B will not fall lower than the 50 point shown in Fig. 1—that is, beneath the level of the liquid when the spoon is full—but may turn back readily.

I am aware that medical spoons have before been used with hinged covers; but these 55 articles were never intended to dip up the material, and are not adapted to the service for which my device is designed.

I am aware of Patent No. 135,141, of 1873, in which the guard is not hinged, and has an 60 aperture through which the contents of the spoon pass into the mouth. Such construction is not sought to be covered in this application.

What I claim is—
65
As a new article of manufacture, a mustache-spoon having an imperforate guard, B, secured by a hinge, *b*, to one side of the bowl, so that it will not fall as low as the plane of the upper edges of said bowl, and having the 70 opposite side left open, as shown, the whole being adapted to serve as and for the purposes set forth.

DAVID G. WILLIAMS.
